UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

FOLDING-MACHINE.

1,255,540.

Specification of Letters Patent. Patented Feb. 5, 1918.

Application filed December 4, 1915. Serial No. 65,067.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Folding-Machines, of which the following is a specification.

My invention is applicable in folding machines for folding the margins of open or closed vamps, quarters, foxings, tongues and other parts of shoe uppers, and other flexible material used, for instance, in the manufacture of gloves, pocketbooks and other articles, and is applicable for operation on leather, cloth and other fabrics.

In folding the margin of flexible material it is usual to apply a narrow band of cement to the margin lengthwise of the margin, so that when the fold of the margin is laid upon the body of the margin a layer or layers of cement shall be interposed between the fold and the body for the purpose of holding the fold of the margin in folded relation. The object of thus cementing the fold to the body of the margin is to maintain the fold in contact with the body while the material is passing through the various stages of operation thereon in its course through the factory for forming the finished product.

The folding of the margin is usually accomplished by machinery employing step-by-step or intermittent feeding movements for feeding the margin of the material past snipping, folding and fold-pressing instrumentalities.

The folds of the margins heretofore folded on machines of this character have frequently been subject to the objection that the inner edges of the folds would rise from the bodies of the margins, which would make the subsequent operations upon the margins difficult, and also result in an inferior product for the reason that the folds of the margins thus rising from the bodies of the margins would cause unnecessary and undesirable thickness or bulkiness of the margins.

It is the object of my invention to provide a step-by-step folding machine employing novel fold-pressing means whereby equal pressure throughout the fold of the margin is assured; and further to provide a folding machine employing fold-pressing means whereby pressure upon the inner edge of the

folded margin is assured in order to press 55 said inner edge of the fold firmly upon the body of the fold, whereby the fold is maintained cemented to the body during subsequent operations upon the flexible material.

It is a further object of my invention to 60 provide a step-by-step folding machine employing a pivoted fold-presser arranged to yield on its pivot during the pressing function in a direction transverse to the plane of its pressing-face and to be operated by a 65 force applied in a direction transverse to its yielding movement; further to provide means for mounting and operating the pivoted fold-presser to insure a yielding movement of the fold-presser crosswise on its 70 pivot, while pressing the margin, at substantially right angles to the plane of the pressing-face of the fold-presser; further, to provide a yieldable fold-presser with a pressing-face, a pivot, and an operating guide, with 75 the walls of the operating guide at substantially right angles to said pressing-face, and further said pivot located substantially at the point of intersection of the sides of said right angle; and, further to provide an oscillating arm having slide-connection with said operating guide so arranged that a right line at right angles to said pressing-face and parallel to said operating guide intersects said pivot and the axis of oscillation of said oscillating arm when said pressing-face is in 80 pressing relation.

The invention will be further readily understood from the following description and claims, and from the drawings, in which 90 latter:

Figure 1 is a side elevation of so much of a folding machine as is necessary to illustrate my invention.

Fig. 2 is an end elevation of the same. 95

Fig. 3 is a plan view of the same, partly broken away.

Fig. 4 is a rear end elevation of the operating means for the fold-presser.

Fig. 5 is a side elevation of the operating 100 means for the fold-presser, the fold-presser being shown in section on the line 5—5 of Fig. 3, in connection with a piece of flexible material, and in the relation in which the fold-presser is about to exert pressing action 105 upon the fold being laid.

Fig. 6 is a similar view, showing the fold-presser at the point of completion of the

pressing function, with the presser shifted with relation to its pivot.

Fig. 7 is a side elevation of the same viewed from the side opposite to that shown in Fig. 6.

Fig. 8 is a vertical section of the same, taken on the line 8—8 of Fig. 6.

Fig. 9 is a diagrammatic representation showing the relations of the parts at the completion of the pressing function of the fold-presser when there is no work in the machine; and,

Fig. 10 is a similar view of the parts showing their relations upon the completion of the pressing of the fold when there is work in the machine.

I have exemplified my invention as employed in a folding machine such as shown, described and claimed in my application for Letters Patent of the United States on improvements in folding machines, Serial No. 634,485, filed June 21, 1911.

My present invention is an improvement upon the devices shown, described and claimed in my application Serial No. 46,520, filed August 20, 1915.

In the present exemplification of my invention the main frame of the machine is represented at 11. There is a suitable material-support 12 having a material supporting surface 13.

The step-by-step or intermittent feeding movements may be accomplished by means of a feeding-foot 14 which coacts with a suitable feed-roll 15. 16 is a snipping knife which is arranged to reciprocate by suitable means so as to snip the folded margin, that is, provide it with cross incisions suitably spaced apart, for instance, to correspond with the distances of the step-by-step feeding movements. The feeding means intermittently feed the margin being folded past a suitable folding device, exemplified as a folding block 17, having a plow-shaped or curved folding face 18, for curling the margin to be folded preparatory to the action thereon by the pressing-device, a presser-foot 19 being arranged to press upon the material between the interims of feeding movements thereof, all as more fully shown and described in my aforesaid applications, instanced as an exemplification and not as a limitation.

The fold-presser, exemplified at 21, is provided with a pressing-face 22, which coacts with an anvil 23, shown as part of the material-supporting face 13, for pressing the fold 24 upon the body 25 of the margin of the flexible material 26 being folded. The meeting faces of the fold and body of the margin are provided with a suitable band of cement which extends lengthwise of the margin.

The anvil has a pressure-face 27, with which the pressing-face 22 coacts. This

pressure-face may be horizontal, as shown, or placed at any desired angle with relation to the horizontal, or be in vertical position, and it may be parallel with the material-support proper, or at an angle thereto, as 70 may be desired.

In the present exemplification, the fold-presser is provided with a pivot-slot 31, the major axis and side walls of which are exemplified as parallel with each other and 75 at right angles to the pressing-face 22. The fold-presser is arranged to normally oscillate about a pivot 32. The pivotal axis of the pivot is in substantially the plane extended of the pressure-face 27 of the anvil. 80 The pressing-face of the fold-presser is in close proximity to the pivot of the fold-presser so as to reduce the path of movement of the pressing-face as much as possible.

The pivot of the fold-presser is shown as comprising the shaft 33 and a bushing 34 thereabout, which bushing may be journaled about the shaft in the form of a roller.

The body of the fold-presser is arranged 90 to move crosswise on its pivot, and means for oscillating the fold-presser are provided which apply a moving force to the fold-presser exerted in a direction crosswise of its yielding movement, whereby the fold-presser is free to yield on its pivotal axis, the construction being such preferably that when the fold-presser is at the point of completion of its pressure movement its 95 pressing-face is parallel with the coacting 100 face of the anvil regardless of the extent of the yielding movement of the fold-presser.

I have exemplified the operating means for the fold-presser as comprising an operating guide exemplified as a slot 36 in the tail 37 of the fold-presser, the guiding walls of the operating guide being shown at substantially right angles to the plane of the 105 pressing-face 22.

A lever 39 has a bearing 40 about a shaft 41 located in bearings 42 of the frame. One arm 43 of the lever 39 has operating connection with the guide-slot 36, exemplified as a slide-block 44 reciprocating in the guide-slot and connected with the arm 43 by means of a pin 45 journaled therein and located in a bearing 46 of the arm 43.

The other arm 50 of the lever 39 is operated by means of a drive-shaft 51 journaled 120 in a bearing 52 of the frame, the drive-shaft having thereon an eccentric stud 53 which may be in the form of a screw screwed into the drive-shaft eccentrically to the drive-shaft. A slide-pin 54 is slidable in a bearing 55 of the arm 50 and has a bearing 56 about the stud 53. When the drive-shaft rotates, the slide-pin follows the movements of the eccentric stud 53 and slides in the bearing 55, for rocking the lever 39.

The bearings 40, 46 and 55 are preferably comparatively long bearings so as to transmit oscillating motion to the fold-presser without binding of the parts.

5 Means are provided for causing resilient yield of the fold-presser, accomplished in the present instance by means of a helical spring 61 exerting pressure between the fold-presser and the bushing 34 for normally resiliently holding the fold-presser downwardly, that is, toward the coacting face of the anvil. The spring also maintains the parts in firm operative relation during operation. The spring is shown received in a bore 63 of the fold-presser and in a bore 62 of an adjusting bolt 64 adjustably threaded in the threaded bore 63, the turning of the bolt adjusting the tension of the spring. The inner end of the spring is shown received in the pivot-slot 31 of the fold-presser.

When the pressing-face 22 is at its point of closest normal approach to the coacting face of the anvil it is preferably parallel with and but slightly spaced from said coacting face a distance slightly less than the thickness of the thinnest material it is desired to press. When material is pressed between the pressing-face and the coacting face of the anvil, the pressing-face will yield with relation to said coacting face a distance determined by the thickness of the folded margin being pressed. The thicker this folded margin is, the greater will be the yield of the fold-presser, the pressing-face of the fold-presser being however parallel with the coacting face of the anvil at the completion of its pressure movement regardless of its distance from the coacting face of the anvil.

40 The fold-presser yields crosswise on its pivot according to the thickness of the folded margin being pressed, this yield causing a shifting of the operating connection between the operating means of the fold-presser and the fold-presser, this shifting being permitted by reason of the fact that the force applied by these operating means is transverse to the direction of movement to the fold-presser.

I have in Figs. 9 and 10 diagrammatically represented the action of the fold-presser and its operating parts shown in the present exemplification during the pressing operation.

Referring to Fig. 9 the point *a* designates the pivotal axis of the lever 39. The point *b* represents the axis of the pin 45, and the point *d* represents the normal position of the pivot 32 with relation to the fold-presser, when the pressing-face 22 of the fold-presser is at its point of normal closest approach to the coacting face 27 of the anvil, in the absence of material between said faces. It will be noticed that when these

faces are in coacting relation, the points *a* *b* and *d* are in a right line which is at right angles to said faces, the point *d* being at substantially the point of intersection between the sides of said right angle.

70 Referring now to Fig. 10, which represents the relation of the parts assuming that a comparatively thick folded margin is being pressed between the pressing-face 22 and its coacting face 27 of the anvil, it will be noted that the normal point *d*, representing the normal relation of the pivotal axis to the fold-presser, is separated from the point *e* representing the assumed or operative pivotal axis of the fold-presser in the 75 relations stated, when employing the present exemplification, and that the operative connection between the slide-block 44 and the slot 36 has shifted to a corresponding extent, represented by the separation of the 80 points *b* *c* in Fig. 10.

85 The pressing-face 22 and its coacting anvil-face are parallel, when they are in pressing relation, regardless of their extent of separation, so that pressure is insured upon 90 the entire width of the fold of the margin, whereby the inner edge 65 of the fold of the margin is pressed upon the body of the margin with sufficient pressure to maintain adhesion by means of the cement therebetween, so as to prevent separation of the fold from the body of the margin during the 95 subsequent course of the material in its steps of manufacture, compression being also exerted upon the bead 66 of the fold for insuring a thin fold-edge, the initial pressure-contact of the pressing-face being upon said fold-edge.

100 Having thus fully described my invention, what I claim as new and desire to secure by Letters Patent, is:

1. In combination, an anvil having a work supporting surface, a fold-presser having a pivotal connection about which it may be oscillated to engage work on said anvil, means adapted to oscillate said fold-presser to cause the same to press the work upon the anvil, and means comprising said pivotal connection adapted to yield to permit a movement of said fold-presser in a direction at a right angle to the plane of the work supporting surface of the anvil whereby different thicknesses of work may be operated upon and equal distribution of pressure insured, the first said means applying an operating force transversely of the direction of yield of said fold-presser.

115 2. In combination, a pivoted mold-presser having a pressing-face, a pivot about which said fold-presser oscillates to press the work, 120 a guide for said pivot extending at substantial right angles to said pressing-face along which said fold-presser yields, and means for oscillating said fold-presser by a force applied to said fold-presser in a direction 125 130

- transverse to the direction in which said guide extends.
3. In combination, a pivoted fold-presser having a pressing-face, a pivot about which said fold-presser oscillates to press the work, a guide for said pivot at substantial right angles to said pressing-face along which said fold-presser yields, and means for oscillating said fold-presser by a force applied to said fold-presser in a direction transverse to the direction in which said guide extends, said last-named means including shiftable means shiftable with the yielding movement of said fold-presser.
4. In a pressing device for flexible material, the combination of an anvil, a fold-presser having a pressing-face coacting with said anvil, a pivot about which said fold-presser oscillates to press the work, a guide for said pivot extending transversely to said pressing-face along which said fold-presser yields, and means for oscillating said fold-presser comprising a rocker-arm having a slide-connection with said fold-presser extending in the general direction in which said pivot-guide extends.
5. In a pressing device for flexible material, the combination of an anvil, a yieldable fold-presser having a pressing-face which coacts with said anvil, a pivot about which said fold-presser oscillates to press the work, a guide for said pivot extending at substantial right angles to said pressing-face, an operating means for said fold-presser, and operative connection between said operating means and said fold-presser comprising a guide substantially parallel with said pivot-guide.
6. In a pressing device for flexible material, the combination of an anvil, a yieldable fold-presser having a pressing-face coacting with said anvil, a pivot therefor, said fold-presser provided with a slot about said pivot extending at substantial right angles to said pivot and the axis of oscillation of said fold-presser having a pressing-face, an oscillating arm, and a slide-connection between said arm and fold-presser, said slide-connection being substantially in a right line intersecting said pivot and the axis of oscillation of said fold-presser when said pressing-face is in pressing relation, and said right line being substantially at right angles to said pressing-face.
7. In a pressing device for flexible material, the combination of an anvil, a fold-presser having a pressing-face coacting with said anvil, a pivot therefor, said fold-presser provided with a pivot-slot about said pivot, a spring between said fold-presser and pivot normally urging said pressing-face toward said anvil, and means for rocking said fold-presser comprising a rocker-arm, there being an operating guide between said rocker-arm and fold-presser extending substantially parallel to said pivot-slot and to a right line intersecting said pivot and the axis of said rocker-arm when said pressing-face is in pressing-relation throughout the extent of separation of said pressing-face and anvil.
8. In a pressing device for flexible material, the combination of an anvil having a pressing-face, a pivoted fold-presser having a pressing-face coacting with said pressing-face of said anvil, said fold-presser yieldable during the pressing movement in a direction transverse to the planes of said pressing-faces, and means for rocking said fold-presser to press the work applying an operating force in a direction transverse to said yielding movement, whereby said pressing-faces are parallel when in fold-pressing relation throughout variations in distance between said pressing-faces when in fold-pressing relations.
9. In a folding machine for flexible material, the combination of intermittently acting material-feeding means, snipping means, folding means, and fold-pressing means comprising a pivoted fold-presser having a fold-pressing face, said fold-presser yieldable on its pivot during its pressing movement transverse to the plane of its pressing-face, and operating means for said fold-presser applying an operating force thereto in a direction transverse to the yielding movement of said fold-presser during its pressing movement.
10. In a folding machine for flexible material, the combination of intermittently acting material-feeding means, snipping means, folding means, and fold-pressing means comprising a pivoted fold-presser having a fold-pressing face, said fold-presser yieldable on its pivot during its pressing movement transverse to the plane of its pressing-face, and operating means for said fold-presser applying an operating force thereto in a direction transverse to the yielding movement of said fold-presser during its pressing movement, said last-named means comprising a part connected to said fold-presser and shiftable lengthwise of said yielding movement of said fold-presser.
11. In a fold-pressing device for flexible material, the combination of an anvil, a pivot having its center lying in approximately the same plane as the pressing-face of said anvil, a fold-presser having a pressing-face which coacts with said anvil, pivotally mounted on said pivot and yieldable thereon in a direction transverse to the pressing face of said anvil, for permitting the said fold-presser to move on its pivot during the pressing movement in order that the pressing-face of the said fold-presser at the conclusion of its pressing movement may lie substantially parallel with the pressing-face of said anvil, irrespective of the thickness of the material being pressed, and means for operating said fold-presser by

applying an operating force thereto in a line substantially transverse to the direction of said yielding movement.

12. In combination, a fold-presser having a pressing face and a pivotal connection about which it moves toward and from pressing position, said fold-presser being yieldable at said pivotal connection in a direction transverse to the plane of said 10 pressing face, and means for oscillating

said fold-presser applying an operating force thereto in a line transverse to its direction of yield.

In testimony whereof, I have hereunto signed my name, in the presence of two 15 subscribing witnesses.

WILLIAM F. LAUTENSCHLAGER.
